JAMES B. CRANE, OF DALTON, MASSACHUSETTS.

Letters Patent No. 84,263, dated November 24, 1868.

IMPROVEMENT IN THE MANUFACTURE OF PAPER BELTING.

The Schedule referred to in these Letters Patent and making part of the same.

To all whom it may concern:

Be it known that I, JAMES B. CRANE, of Dalton, Berkshire county, Commonwealth of Massachusetts, have invented a new and useful method of Manufacturing Paper Belting, &c.; and I do hereby declare that the following is a full and clear description thereof, reference being had to the accompanying drawing, and to the letters of reference marked thereon.

In the drawing, the figure represents the position generally of the paper-stock in the process, position of rollers, &c.

This invention consists of a new and improved method of manufacturing a fabric of paper, for paper belting and various other purposes, for which this manufactured article is peculiarly adapted.

In forming my paper fabric, the pulp is carried through the first press-rollers by means of a felt, and the fabric that is so formed, I carry over other rollers, varied in number according to the requirements of the case, bringing the first-formed end back to the first press-rollers, where it is run through again, and performs the same journey over the rollers as before, carrying with it, however, the continued stock as the felt delivers it, and so doubles the fabric each time that it completes the circuit. This operation is continued until the fabric has the required number of thicknesses, when the supply of pulp may be cut off, and the rollers allowed to run on with the endless belt of fabric, hardening it to the utmost, if such a quality of fabric be desired, or to whatever degree required.

In the drawings, A A are the first press-rollers, B, the felt, and C C, &c., the auxiliary rollers holding the stock D. E and F are rollers for the purpose of keeping the endless belt, D, of paper from getting out of place. These, however, are not necessary in all cases and may often be dispensed with.

A stretcher, such as is used in ordinary belting, may be used with advantage for keeping the belt tight.

A much stronger fabric may be made by running a fibrous material, such as thread, warp, or cloth in with the thicknesses of belt as they are revolved around the rollers. This fibre is worked in with the pulp as it is carried between the press-rolls. I also render my fabric more flexible, by mixing with it, as it is revolved, a resinous or glutinous substance, by running the belt through a box containing the substance, a roller being placed in the box, and the belt carried down under it through the resin or gluten. Oil may be applied in the same manner, if desired.

The advantages of this process are that I obtain a fabric that is nearly as adaptable as leather for every purpose, and fully equal to it in most cases where the latter is in general use, while my fabric is manufactured and can be supplied at half the price of leather.

In drying the belt of fabric in process of formation, it is not necessary that the same be taken off the rollers for the purpose, as the same may be surrounded by hot air during its formation; and in taking the belt off from the rollers, after it is formed, it may be either cut or unshipped whole, by taking out the rollers, they being arranged so that this can be done conveniently.

Now, having described my invention,

What I claim as new, and desire to secure by Letters Patent, is—

The process herein described for manufacturing paper fabric, substantially in the manner and for the purposes herein set forth and described.

JAMES B. CRANE.
